UNITED STATES PATENT OFFICE.

REGINALD A. FESSENDEN, OF ALLEGHENY, PENNSYLVANIA, ASSIGNOR OF ONE-HALF TO GRANT MCCARGO, OF PITTSBURG, PENNSYLVANIA.

INCANDESCENT LAMP.

SPECIFICATION forming part of Letters Patent No. 638,839, dated December 12, 1899.

Application filed August 25, 1899. Serial No. 728,421. (No model.)

To all whom it may concern:

Be it known that I, REGINALD A. FESSENDEN, a citizen of the United States, residing at Allegheny, in the county of Allegheny and State of Pennsylvania, have invented or discovered certain new and useful Improvements in Incandescent Lamps, of which improvements the following is a specification.

In an application, Serial No. 726,395, filed August 7, 1899, I have described and claimed certain improvements in incandescent lamps employing pencils which become electric conductors only when heated. The invention set forth in said application consists, generally stated, in providing a path for electric currents along the pencil for the purpose of heating the pencil to a conducting temperature.

The present invention has for its object certain further improvements in the means for forming a path for the electric current along the surface of the pencil.

In the accompanying drawings, forming a part of this specification, Figure 1 is a sectional elevation of a lamp having my improvement applied thereto, and Figs. 2 and 3 are sectional detail views of parts of the lamp.

In the practice of my invention the supporting-pins 1 1^a are mounted in suitable bearings 2, preferably formed of insulating material and secured to the sides of the dome-shaped shell 3, which has its inner surface highly polished. One of the pins, as 1, projects through the case or shell and is so mounted in its bearing as to be capable of longitudinal as well as rotary movement and is held in normal position, so as to support one end of the pencil 4, by a spring 5, surrounding the pin and bearing at its ends against the bearing 2, and a disk 6, formed of insulating material and secured on the pin. The pencil 4, which is formed of magnesia, kaolin, or other material non-conducting when cold, but becoming a conductor when heated, is provided at its ends with axial holes or sockets for the reception of the ends of the pins 1 and 1^a. The pins bear at their ends, which are preferably made angular or irregular in cross-section, against the inner edges of terminals formed of a spirally-bent piece of

metal 7, embedded in the pencils. These pieces of metal are made of such a size that their outer edges will be flush with the surface of the pencil, and the pitch of the spiral 55 preferably corresponds with the pitch of the threads on the shaft 8. This shaft 8, which has its ends mounted in bearings 9, secured to the shell 3, has an internally-threaded carrier-block 9^a mounted thereon. A block 10, 60 formed of graphite or other conducting material neutralizable as regards its capability of conducting electric currents at high temperatures, is attached to the carrier-block, preferably by a spring 11 or by any other 65 suitable means, whereby the connecting material may be held in rubbing contact with the pencil. The shaft 8 may be rotated so as to cause the block of conducting material to traverse the pencil by any suitable means; 70 but as it is preferred to cause the pencil to rotate during the traverse of the block pinions 12 and 13 are secured, respectively, on the shaft 8 and pin 1^a, said pinions intermeshing with a driving-pinion 14, secured on 75 one end of a shaft 15, which projects through a suitable bearing 16 and has a knob 17 secured to its outer end. As shown in Fig. 3, the pinion 13 is insulated from the pin 1^a. The carrier-block may be held as against rotation with the shaft 8 by any suitable means—as, for example, by a rod 18, secured 80 at its ends to the shell 3 and passing loosely through an upward extension of the carrier-block.

The feed-wires 19 are attached to contact-plates 20 and 20^a, secured to insulating-blocks attached to the shell, and corresponding contact-plates 21 21^a are attached to the disks 5 and 6 on the pins 1 and 1^a. As the pins 1 and 90 1^a are electrically connected to the contact-plates 21 21^a, the rotation of the pins will complete the circuit through the pencil. The contact-plates 20 20^a and 21 21^a are so constructed and arranged that the latter can slide 95 past the plates 20 20^a when the disks 5 and 6 are rotated.

By the rotation of the driving-pinion 14 the block 10, of graphite, will be caused to move along the pencil, which is also rotated, so that 100 a spiral band or, if the block 10 is sufficiently long, a complete coat of graphite will be ap-

plied to the pencil. As the edges of the metal terminals 7 are exposed and flush with the surface of the pencil, a conductor will be formed along the surface of the pencil from terminal to terminal. The passage of the current along the conductor will heat the pencil sufficiently to render it conducting. As soon as the pencil is raised to a high heat the material used to form a conducting-path will be destroyed or rendered neutral, so that the entire current will pass through the pencil.

Although it may require several rotations of the shaft 8 to effect the end-to-end traverse of the carrier-block, the meeting of the contact-plates will not close the circuit, as no current can pass until a conducting-path is formed from terminal to terminal.

It is preferred to place blocks 22, formed of non-conducting material, on the pins 1 and 1^a, adjacent to the ends of the pencils, to serve as supports for the blocks 10.

I claim herein as my invention—

1. In an incandescent lamp, the combination of a pencil non-conductive at low temperatures, but conductive at high temperatures;

a carrier for a conducting material neutralizable at high temperatures, and means for causing the carrier to move along the pencil, substantially as set forth.

2. In an incandescent lamp, the combination of a pencil non-conductive at low temperatures, but conductive at high temperatures; a carrier for a conducting material neutralizable at high temperatures, and means for simultaneously rotating the pencil and shifting the carrier along the pencil, substantially as set forth.

3. In an incandescent lamp, the combination of two rotatable pins adapted to support and rotate a pencil, a threaded shaft, a carrier-block mounted on the shaft and means for simultaneously rotating the shaft and pins, substantially as set forth.

In testimony whereof I have hereunto set my hand.

REGINALD A. FESSENDEN.
